CLAIM

The ornamental design for a scrub pad handle, as shown and described.

DESCRIPTION

FIG. 1 is a perspective view of a scrub pad handle in accordance with the present invention;

FIG. 2 is a left-side view, the right-side view being a mirror image thereof;

FIG. 3 is a top view;

FIG. 4 is a front view; and,

FIG. 5 is a back view.

The broken lines in FIG. 1 show the placement of a scrub pad, and form no part of the design as claimed.
